Inventor.

B. F. Cowan

UNITED STATES PATENT OFFICE.

B. F. COWAN, OF MEMPHIS, TENNESSEE.

FIREPLACE.

Specification of Letters Patent No. 31,785, dated March 26, 1861.

To all whom it may concern:

Be it known that I, B. F. COWAN, of Memphis, in the county of Shelby and State of Tennessee, have invented a new and useful Improvement in Fireplaces; and I do hereby declare that the following is a full, clear, and exact description of the same, reference being had to the accompanying drawings, forming a part of this specification, in which—

Figure 1, is a front view of a fire place constructed according to the plan of my invention. Fig. 2, is a vertical transverse section of the same.

Similar letters of reference in each of the several figures indicate corresponding parts.

The nature of my invention consists, 1st, in the combination of a grate with an air space at the back thereof, and a passage communicating with the outside of the apartment or house in which the grate is situated, whereby the air consumed is taken from the outside of the apartment so as to keep the air inside of the room pure, and also assist in a more perfect radiation of the heat, in the manner hereinafter described.

It consists, 2nd, in the combination with the above mentioned grate, air space and air passage of the peculiar form of radiator shown, substantially as hereinafter described.

To enable others skilled in the art, to make and use my invention, I will proceed to describe its construction and operation.

A, represents the grate of a fire place; it may be constructed in the usual manner. Behind this grate, I construct an air space B, said air space extending the entire width of the grate and being closed on a level with the top of the same, as represented in the drawing. The air space connects with a passage C, leading from the outside of the

house or apartment and used for the purpose of admitting air into the space or chamber B, from whence it is forced through the grate and the body of the coal contained therein, into the room, thereby insuring the deliverance of a greater amount of heated air than by the usual method of feeding the fire from the inside of the room.

D, is the back or radiator; it is constructed in the manner represented in the drawings. The peculiar shape which I have there represented, I deem the best to secure a perfect radiation of the heat.

E, is a flue leading from the top of the back or radiator; it serves as an escape passage for the products of combustion.

It will be observed that the air space B, is closed on a level with the top of the grate. This is done in order to force the air through the body of the coal and prevent its passage up behind the same and so on up the chimney where it would escape.

I sometimes construct my grate in a manner to have the front thereof form a slight longitudinal concave.

What I claim as my invention and desire to secure by Letters Patent, is—

1. The arrangement of a grate A, with an air space B, in the manner described, at the back thereof, and a passage C, communicating with the outside of the apartment or house in which the grate is situated, as and for the purposes set forth.

2. The combination with the above mentioned grate A, air space B, and air passage C, of the form of radiator D, shown, as and for the purposes set forth.

B. F. COWAN.
